ALVIN C. KNECHT, OF DAYTON, OHIO

ICED DRINK ACCESSORY

Application filed September 4, 1929. Serial No. 390,383.

This invention relates to the icing of sodas or other iced drinks, and has for its principal object the provision of a member cooperating with a drinking tube to confine the ice in a 5 glass to the area from which the liquid is drawn into the drinking tube.

Another object of the invention is the provision of a member which may be attached to a drinking tube so that upon insertion of the 10 tube within a glass of iced liquid the ice will be confined to the bottom of the glass adjacent the opening of the drinking tube; the member being very simple in construction, inexpensive to produce and of such 15 nature that it may be discarded after a single usage.

Other objects and advantages of the invention will be apparent from the following description, the accompanying drawings and 20 the appended claims.

In the drawings,

Fig. 1 is a vertical sectional view of a drinking glass, in which is illustrated a preferred embodiment of the invention; and

Fig. 2 is a plan view of the ice retaining member.

In imbibing iced drinks such as are served within a drinking glass or a similar container at soda fountains and the like, and which 30 comprise a liquid and lump or cracked ice for chilling the liquid, usually partaken of by means of a drinking tube such as a paper drinking straw, the chilling effect of the ice is not effectively imparted to the liquid as the 35 ice remains on top while the liquid is withdrawn by means of the drinking tube from the bottom portion of the glass. This invention discloses a means for effectively chilling the liquid as it is drawn into the drinking tube by confining the ice to the area adjacent 40 the opening of the drinking tube.

Referring to the drawings, in which like characters of reference designate like parts of the various views, the numeral 10 designates a receptacle such as an ordinary drinking glass commonly employed for containing sodas or beverages and which may be of any suitable design. The receptacle serves as a 45 container for the liquid 11 and ice 12 which is added to the liquid to cool it. The ice is

usually added in the form of small chips or pieces or of a size referred to as cracked ice. A drinking tube 13, such as the commonly used paper drinking straw, is provided for imbibing the liquid and may be of 55 any suitable material such as that mentioned; or it may be of a more durable nature. Positioned upon the drinking tube 13 adjacent the lower end thereof is a perpendicularly disposed member 14 which, upon insertion of 60 the tube 13 within the receptacle 10, is adapted to force the ice 12 which normally floats at the top of the liquid down toward the bottom of the receptacle 10. Thus when the liquid is partaken of by means of the tube 65 13 the liquid 11 will be drawn through the closely packed ice 12 which is confined to an area surrounding the tube end and will thereby be properly chilled before entering the tube 13. The member 14 is usually spaced 70 a sufficient distance from the end of the tube 13 to permit the tube end to reach the bottom of the glass when the ice is moved down by the member 14 against the bottom of the glass. A spacing of an inch or so is generally 75 sufficient to accommodate a suitable quantity of ice but this distance may be varied as desired.

The member 14 is preferably disk like in shape although it may be made either flat or 80 be somewhat cupped, and may be of any shape suitable for moving the ice into the bottom portion of the glass when the member is introduced thereto. The member 14 is provided with an opening 15 to permit the insertion of the tube or straw 13 which is preferably held thereto by frictional engagement, as the hole 15 is just large enough to receive the straw without deforming it. The member 14 may, however, be formed as an integral 85 part of the drinking tube. In a preferred form member 14 is made of cardboard, although it may readily be made of other suitable material, and is provided with a plurality of openings 16 through which the liquid passes as it is drawn from the glass into engagement with the ice and through the tube 13. The disk 14 is preferably of a size sufficiently less than the inside dimension of the 90 glass to permit its easy insertion therein, but 95 100

not small enough to permit the ice to pass between the wall of the glass and the edge of the disk. The member 14 when made of cardboard is very inexpensive to produce and may be thrown away after a single usage thereby eliminating the need for washing or other attention after use. The surface of the member 14 provides a suitable area for printing or the insertion of an advertisement.

There is therefore provided an extremely inexpensive article of great practical value in providing the chilling effect so desirable in an iced drink, and which when made of cardboard is so inexpensive that it may be disposed of with the soda straw after use. The ice confining disk may be attached to the straw with great facility, and may be slipped along the straw to a distance from the straw end approximately in accordance with the amount of ice in the drink. The entire drink is cooled effectively, and it is unnecessary to stir the drink or wait until the ice melts to provide the desired cooling effect.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. Means for confining ice within a drinking glass or the like containing iced liquid, comprising, a perforate member adapted to be received within the lower portion of the glass to confine ice thereunder, said member having holes in one of which a drinking tube may be inserted for frictional engagement therewith.
2. In combination, a glass or the like for holding iced liquid, a drinking tube, and a perforate member attached to said tube, said perforate member being of a diameter of the same order as the diameter of the adjacent portions of the glass and adapted to confine ice thereunder upon insertion within the glass.

In testimony whereof I hereto affix my signature.

ALVIN C. KNECHT.
